CLAIM

We claim the ornamental design for a bite block, as shown and described.

DESCRIPTION

FIG. 1 is an upper perspective view of our new design;
FIG. 2 is a lower perspective view thereof;
FIG. 3 is a top plan view thereof;
FIG. 4 is a left elevational view thereof, the right elevational
view being identical;
FIG. 5 is a back elevational view thereof; and,
FIG. 6 is a front elevational view thereof.

The broken lines along the handle are for the purpose of
illustrating portions of the article and form no part of the
claimed design.
